REFRIGERATING SYSTEM

Wayne D. Jordan, Chicago, and Paul D. Van Vliet, Galesburg, Ill., assignors to The Liquid Carbonic Corporation, Chicago, Ill., a corporation of Delaware

Application February 20, 1941, Serial No. 379,740

9 Claims. (Cl. 62—126)

The present invention relates to improvements in refrigerators and refrigerator systems, particularly of the type wherein mechanical refrigeration is provided for maintaining the storage compartments cold.

More specifically, the invention relates to that type of refrigerators wherein there are provided a plurality of storage compartments from which the contents of the compartments are adapted to be removed through the top.

In this type of refrigerators, particularly where the storage compartments are comparatively deep, there is difficulty in maintaining an even temperature throughout the height of the compartments and, furthermore, where a plurality of storage compartments are provided, there has been difficulty in maintaining the temperature of all of the compartments substantially equal.

Other objects and advantages of our invention will appear more fully hereinafter in the appended specification and claims.

For the purpose of disclosing our invention, we have illustrated an embodiment thereof in the accompanying drawings, in which:

Fig. 1 is an elevation, more or less diagrammatic, with the cabinet in section, of a refrigerator embodying our invention;

Fig. 2 is a side elevation of one of the refrigerating compartments or sleeves;

Fig. 3 is a side elevation of the same, looking at the opposite side;

Fig. 4 is an end elevation;

Fig. 5 is a detail view showing a connection from the one set of coils to the other;

Fig. 6 is a detail sectional view of one of the sleeves;

Fig. 7 is a detail sectional view of one of the sleeves before the same is shaped;

Fig. 8 is a sectional view on the line 8—8 of Fig. 7;

Fig. 9 is a detail section of a restrictor in the connection between one set of coils and another set;

Fig. 10 is a diagrammatic view of the circuit arrangement of the coils; and

Fig. 11 is a diagrammatic view of another circuit arrangement.

In the embodiment illustrated, the refrigerator comprises an enclosing cabinet 1 in which are arranged a plurality of sleeves or storage compartments 2, 3 and 4 and preferably half length sleeve 5 which delivers to a sump or low side accumulator 5a. The usual refrigerating mechanism, including a compressor 6, driven by an

electric motor, 7 and delivering to a condenser 8, is arranged in a compartment within the casing 1.

Each of the sleeves 2, 3 and 4 is of substantially the same construction and comprises an inner tank 10 of full sleeve dimensions, to which is hermetically sealed on the four sides thereof an outer sheet 11 in which channels or corrugations 12 have been formed. In the construction of the complete sleeve, there is provided a single sheet 10 of material of such dimensions as to, when formed up, provide the four sides of the tank or sleeve. Hermetically sealed on the outer surface of this sheet is a second sheet having formed therein suitable corrugations or channels which provide refrigerant passages between the inner and outer sheets. The laminated structure thus provided is then bent into rectangular form with its adjacent edges secured together, preferably by welding or the like, and the bottom is formed by welding a bottom sheet within the sleeve. Preferably, the outer sheet is secured and sealed to the inner sheet by welding between the corrugations or other suitable means.

In the formation of the sleeve from the laminated sheet, as above, difficulty has been experienced with the flattening of the corrugations 12 at the point where the corner bends are made and, as a result, restrictions are apt to be formed in the channels. To overcome this difficulty, when the laminated sheets are made, the corrugations at the point where the bends are to take place, are slightly enlarged, as at 13, and within these enlarged portions, U-shaped channels 14 are inserted with the bight of the U outwardly. To prevent displacement, the channels may be welded in position. By this arrangement, when the laminated sheet is bent to form the completed sleeve, the corrugated portion at the bend is reenforced to such an extent that it will not flatten down and the area of the channel is maintained substantially constant throughout.

Each of the sleeves 2, 3 and 4, is provided with two sets of corrugations or passageways, one at the top portion of the sleeve and one at the bottom portion of the sleeve. These two sets of corrugations are separate and distinct so that the refrigerant does not pass directly from one set into the other.

In the arrangement illustrated, the sleeves are so arranged that the refrigerant passing from the condensing unit 8 initially enters the lower coil or set of corrugations of the sleeve 2. The refrigerant enters the coil at the top, passing downwardly through the coil, and emerges from the bottom corrugation of the coil into the conduit 15.

This conduit is connected with the top of the lower coil of sleeve 3 and the refrigerant passes into the top of the lower coil, thence downwardly through the coil and out of the bottom into the conduit 16 which, it will be noted, is connected to the top of the lower coil of sleeve 4. After passage through the lower coil of sleeve 4, the refrigerant, by conduit 17 passes into the top of the upper coil of sleeve 4 passing through this coil into conduit 18 and thence into the top and out of the bottom of this sleeve, the refrigerant eventually being delivered by conduit 19 to the top of sleeve 5 and thence back to the compressor in the usual manner.

By using a "split" circuit, as above, substantial advantage is gained in the evenness of temperature from the top to the bottom of the sleeves and from end to end in the cabinet whereas without this split circuit a relatively wide variation of temperature occurs, with maximum temperature at the top of each sleeve.

In addition to the provision of the "split" circuit of refrigerator tubes or coils, as above described, we provide means for building up a resistance to the refrigerant flow in the upper coils. One way this resistance may be provided is the arrangement within the conduit 17 of a restriction which may consist of a bushing 20 having a restricted opening 21 therein. As a result of the insertion of such a restriction, the average gas pressure in the lower coils is substantially higher than the average gas pressure in the upper coils, resulting in the temperature differences desired to hold the top and bottom temperatures substantially equal. By this provision of the restriction, as above described, we are enabled to get the same temperature effect, irrespective of the number of storage compartments or sleeves or, in other words, we are enabled to get the same temperature effect in short and long cabinets. Over-all pressure drop varies with the number of sleeves but, by the use of the restrictor or restricted passage, which is properly proportioned in accordance with the number of sleeves, the differential between top refrigerant temperature and bottom refrigerant temperature may be held the same for small or large cabinets. In other words, we are enabled to maintain a temperature differential between the lower sets of coils and the upper sets of coils, suitable for requirements, by the simple expedient of providing a small bushing with a properly selected orifice therein.

If desired to obtain a colder temperature in, say, the sleeve 5, such a restrictor as is illustrated in Fig. 9, may be inserted between the top coil of sleeve 2 and the coil 5. By this arrangement, a greater pressure drop may be obtained between the coil 5 and the remaining coils and, consequently, a lower temperature maintained in the sleeve 5.

While the provision of the restrictor illustrated in Fig. 9 is the simplest expedient for accomplishing the results sought, it is obvious that the same results may be obtained by modification thereof such, for instance, as that of reducing the area of the tubes or corrugations in the upper sleeves as compared to the area of the tubes or corrugations in the lower sleeve. However, such an arrangement, of course, while permissible and possible, is not as commercially practical as the arrangement illustrated, namely, that of providing a restrictor bushing, as heretofore described.

We claim as our invention:

1. A combined storage receptacle and evap-

orator for refrigerators comprising a substantially rectangular inner sleeve having a closed bottom and an outer sleeve having channels or corrugations formed therein extending horizontally thereof and inter-connected to provide refrigerant passages between the outer and inner sleeves, said outer sleeve having a gas-tight junction with the inner sleeve between and outside of said corrugations and hollow reenforcing members arranged in said corrugations between the inner and outer sleeves at the bend points of said sleeves.

2. A combined storage receptacle and evaporator for refrigerators comprising a substantially rectangular inner sleeve having a closed bottom and an outer sleeve having channels or corrugations formed therein extending horizontally thereof and inter-connected to provide continuous passages between the inner and outer sleeves, said outer sleeve having a gas-tight junction with the inner sleeve between and outside of said corrugations, and U-shaped bridge members mounted in said corrugations between the inner and outer sleeves and at the bend points of the outer sleeve.

3. A combined storage receptacle and evaporator for refrigerators comprising a substantially rectangular inner sleeve having a closed bottom and an outer sleeve having channels or corrugations formed therein extending horizontally thereof and inter-connected to provide continuous refrigerant passages between the inner and outer sleeves, and means having a passageway formed therein disposed in said corrugations between the inner and outer sleeves at the bend points of the outer sleeve to prevent the collapse of the outer sleeve at said bend points.

4. A combined storage receptacle and evaporator for refrigerators comprising a substantially rectangular inner sleeve having a closed bottom and an outer sleeve having channels or corrugations formed therein extending horizontally thereof and inter-connected to provide continuous refrigerant passages between the inner and outer sleeves, means for reenforcing said corrugations at the bend points of the outer sleeve to prevent the collapse thereof, and means for making a gas-tight junction between the outer and inner sleeves between the corrugations.

5. A combined storage receptacle and evaporator for refrigerators comprising a substantially rectangular inner sleeve having a closed bottom and an outer sleeve having channels or corrugations formed therein extending horizontally thereof and inter-connected to provide continuous refrigerant passages between the inner and outer sleeves, said corrugations being enlarged at the bend points of the outer sleeve, reenforcing means disposed in said enlarged portions for preventing collapse of the corrugations at the bend points, and means forming a gas-tight junction between the inner sleeve and the outer sleeve.

6. A combined storage receptacle and evaporator for refrigerators comprising a substantially rectangular inner sleeve having a closed bottom and an outer sleeve having channels or corrugations formed therein substantially horizontally thereof and inter-connected to provide continuous refrigerant passages between the inner and outer sleeves, said outer sleeve having a gas-tight joint with the inner sleeve between said corrugations, said corrugations being enlarged at the bend points therein, and U-shaped reenforcing channels inserted in said enlarged portions to

prevent collapse of the corrugations at the bend points.

7. A refrigerant system comprising in combination a condensing unit, a plurality of evaporators arranged to define a plurality of spaces to be cooled, each evaporator comprising an upper and lower coil, the connection between successive coils of the evaporators and the connections of said coils to the condensing unit being such as to cause the refrigerant to pass from the condenser through the lower coils of the evaporators in series and then through the upper coils of the evaporators in series in reverse order prior to its return to the condenser, and means for providing a pressure differential of the refrigerant between the series of lower coils and the series of upper coils.

8. A refrigerating system comprising in combination a condensing unit, a plurality of evaporators arranged to define a plurality of spaces to be cooled, each comprising an upper and a lower coil, the connection between said coils and successive coils of the evaporators and the connections of the coils to the condensing unit being

such as to cause the refrigerant to pass through the lower coils of the evaporator in series and then through the upper coils of the evaporator in series in reverse order prior to its return to the condenser, and a restricted passageway formed in the connection between the lower series of coils and the upper series of coils.

9. A refrigerating system comprising, in combination, a condensing unit, a plurality of evaporators arranged to define a plurality of spaces to be cooled, each comprising an upper and a lower coil, the connections between the successive coils of the evaporators and the connections of said coils to the condensing unit being such as to cause a refrigerant to pass through the lower coils of the evaporators in series and then through the upper coils of the evaporators in series prior to its return to the condenser, and means for restricting the passage of refrigerant through the upper coils to thereby provide a lower average refrigerant pressure in the upper series than in the lower series of coils.
